UNITED STATES PATENT OFFICE.

WILLIAM A. FITZSIMMONS, OF OMAHA, NEBRASKA.

ICING DEVICE FOR LIVESTOCK CARS.

Application filed September 17, 1924. Serial No. 738,142.

To all whom it may concern:

Be it known that WILLIAM A. FITZSIMMONS, a citizen of the United States, residing at Omaha, in the county of Douglas and

5 State of Nebraska, has invented certain new and useful Improvements in Icing Devices for Livestock Cars, of which the following is a specification.

The invention relates to icing devices for 10 live stock cars, and has for its object to provide a device of this character extending longitudinally of a live stock car, and having its ends slidably mounted in vertically disposed guide channels carried by the end 15 walls of the cars, and on which device ice may be placed, and as it melts the cool water therefrom will drop onto the backs of hogs and will keep them moving, especially the hogs located centrally of the car where air 20 does not reach the same, consequently suffocating incident to crowding is obviated.

A further object is to form the device from screen material, preferably made from rods and having upstanding side members 25 for preventing lateral displacement of ice when placed thereon. Also to provide means controllable from outside the car, whereby the ice supporting device may be raised to a position adjacent the top of the 30 car when not in use.

With the above and other objects in view the invention resides in the combination and arrangement of parts as hereinafter set forth, shown in the drawing, described and 35 claimed, it being understood that changes in the precise embodiment of the invention may be made within the scope of what is claimed without departing from the spirit of the invention.

40 In the drawing:—

Figure 1 is a perspective view of the body of the car, showing one side removed and the icing device therein.

Figure 2 is a perspective view of the end 45 of the car, showing the guide brackets.

Figure 3 is a perspective view of one of the members to which the ends of the ice receiving tray are secured.

Figure 4 is a perspective view of one of 50 the guide channels.

Figure 5 is a perspective view of the other guide channel.

Figure 6 is a perspective view of one of the angle irons for the ends of the trays.

55 Figure 7 is a perspective view of the tray.

Figure 8 is a perspective view of one of

the supporting brackets for the center of the tray.

Referring to the drawing the numeral 1 designates a conventional form of live stock 60 car, of the type used for shipping hogs and 2 the usual slat sides thereof through which air circulates to the interior of the car. It has been found where hogs are shipped in cars of this character, the hogs crowd each 65

other to the center of the car, thereby weakening the hogs in the center of the car, and causing their death by suffocation. The hogs adjacent the sides of the car receive 70 sufficient air, which air does not reach the hogs in the center of the car. It has been

found if cold water is allowed to drip on the backs of the hogs, they will move about in the car, consequently will not crowd to the center of the car, and to accomplish this 75

result a horizontally disposed tray 3 is provided, which extends longitudinally of the car and is formed from heavy wire or rods.

The tray 3 is provided with vertically disposed side members 4, which side members, 80

when ice is placed in the tray will prevent transverse displacement thereof and hold the ice on the tray so that it will slowly melt, and cool water therefrom will drop 85

downwardly on the backs of the hogs in the stock car, and cause the hogs to move about 90

in the car. Secured to the ends of the tray 3 are right angularly shaped members 5, which members have their vertical flanges 6 secured to the horizontally disposed bars 7 by means of bolts 8. The ends of the bars 7 are provided with rectangular shaped enlargements 9, which enlargements are vertically 95

slidable in the channels of the vertically disposed channel members 10, which are secured to the end walls 11 of the car, and when the enlargements 9 are in the bottoms of the channels 10 the tray is held in a horizontal position and against sagging incident to weight thereon. However to further 100

brace the device the sides 2 of the car are provided with L-shaped brackets 12, which have one of their arms 13 disposed under the tray for supporting the same, therefore it will be seen that the tray with 105 the ice thereon will be thoroughly supported and braced.

The bars 7 have their upper sides provided with eyes 14, to which are connected flexible members 15, which extend upwardly 110 over the rollers 16, carried by the ends 11 of the car, and thence downwardly outside

the ends 11 of the car to a position where they can be easily grasped by persons outside the car for raising the tray to a position adjacent the top of the car where it 5 will not interfere with the use of the car for other purposes, and when it is not desired to use the icing device. The ends of the flexible members 15 are provided with rings 17 adapted to be hooked over the hooks 18 in 10 the end walls 11 of the car for holding the tray in raised position when not in use.

From the above it will be seen an icing device is provided for live stock cars, which is simple in construction, and one whereby 15 the car will be maintained cool, and at the same time water will drop from the melting ice onto the backs of hogs or other elements and cause the same to move about in the car. Although the device has been described primarily for use in connection with 20 cars in which hogs are shipped, it is to be understood that it may be used in connection with live stock cars of any kind.

The invention having been set forth what 25 is claimed as new and useful is:—

1. The combination with a live stock car having end and side walls, of an icing device, said icing device comprising a horizontally disposed ice receiving tray formed 30 from screen material, the ends of said tray being provided with angle members, vertically disposed guide channels carried by the

end walls of the car, horizontally disposed bars, said angle members being secured to said bars, enlargement carried by the ends 35 of said bars and slidably mounted in the guide channels and flexible members connected to said bars and extending upwardly and through the end walls of the car and terminating outside the car and forming 40 means whereby said tray may be held in raised position.

2. The combination with a horizontally disposed ice receiving tray disposed in a stock car, guide channels carried by the opposite walls of the car and in which the ends 45 of the tray are slidably mounted, of a flexible member connected to the ends of the tray, said flexible members extending upwardly over pulleys carried by said walls 50 and through the walls, and means carried by the walls outside the car to which the flexible members may be attached for holding the tray in raised inoperative position.

3. The combination with a live stock car 55 having end walls, of an ice receiving tray extending longitudinally of said car, supporting brackets carried by said end walls and vertically guidable by said brackets and means cooperating with the ends of said 60 tray whereby said tray may be raised and lowered from outside the car.

In testimony whereof I affix my signature.
WILLIAM A. FITZSIMMONS,
